(57) **CLAIM**

The ornamental design for a toilet roll dispenser, as shown and described.

DESCRIPTION

FIG. 1 is a perspective view from one end and to the left side of one embodiment of a toilet roll dispenser, in an open unfolded condition and showing the interior of my new design;

FIG. 2 is a perspective view from the one end and to the right side of the toilet roll dispenser, as shown in FIG. 1, in an open unfolded condition and showing the exterior of my new design;

FIG. 3 is an elevational view from the one end of the toilet roll dispenser, as shown in FIG. 2, in a closed folded condition;

FIG. 4 is an elevational view from the other end of the toilet roll dispenser, as shown in FIG. 2, in a closed folded condition;

FIG. 5 is an elevational side view of the toilet roll dispenser, in a closed folded condition, and the other side matches;

FIG. 6 is a top plan view of the toilet roll dispenser, in a closed folded condition; and,

FIG. 7 is an elevational view from the one end of the toilet roll dispenser, in the open unfolded condition.
